[57] CLAIM

The ornamental design for a purse, as shown and described.

DESCRIPTION

FIG. 1 is a perspective view of a purse showing my new design with the front flap fully open and the rear flap partially open;

FIG. 2 is a bottom rear perspective view thereof;

FIG. 3 is a left end elevational view thereof;
FIG. 4 is a top plan view thereof with the front flap partially broken away and omitted for convenience of illustration;

FIG. 5 is a reduced scale front perspective view of the purse in a closed condition; and

FIG. 6 is a rear perspective view of FIG. 5.
